UNITED STATES PATENT OFFICE.

HENRY E. VAN NESS, OF ELMIRA, NEW YORK.

YARN CLEANER.

Original application filed February 14, 1923, Serial No. 618,883. Divided and this application filed June 4, 1925. Serial No. 34,787.

This invention relates to yarn cleaners for eliminating from yarn impurities such as parts of seeds, parts of stems, slubs, specks, grains of sand and other particles before the yarn is made into cloth, and thus improving the quality of the cloth made from the yarn and avoiding the necessity for excessive bleaching of the cloth.

The invention aims to provide a simple device adapted thoroughly to clean a traveling yarn.

A cleaner provided with a number of blades which are mechanically reciprocated rapidly in directions substantially longitudinal of the yarn is described and claimed in my copending application filed February 14, 1923, Serial No. 618,883, of which this application is a division. This parent application is now patent No. 1,541,448, June 9, 1925.

The invention to which the present application is directed relates to mechanical means for reciprocating the blades herein described in detail with reference to the accompanying drawings in which—

Fig. 1 is a top view of the cleaner in which the blades are reciprocated in curves tangential to the yarn;

Fig. 2 is a transverse section of the cleaner shown in Fig. 1 on the line 2—2 of Fig. 1;

Fig. 3 is a rear end view of the cleaner shown in Fig. 1; and

Fig. 4 is a fragmentary side view showing the parts shown at the extreme right-hand end of Fig. 1.

The yarn cleaner shown in the figures has a regular frame 110, the ends of which are provided at their middle with recesses 120, 121 which permit a yarn A to be drawn longitudinally across the middle of the frame below the upper edge thereof. To the end 113 of the frame, which is termed the front end because it is the end from which the traveling yarn enters the cleaner, is attached a tension device 119 which retains the yarn under tension as it is drawn across the frame of the cleaner. The tension device illustrated forms the subject matter of my Patent No. 1,456,263, issued May 22, 1923, and is, therefore, not described in detail or claimed herein.

The top of the frame 110 may be closed by a two-piece cover 126 which provides a slot extending from recess 120 to recess 121. A skirt 132 extends downwardly from the

frame to confine the impurities removed from the yarn in the cleaner.

The sides 115, 116 are of considerable width and have in their upper surfaces guideways 117, 117' extending between the guide holes 141 in the ends 113, 114 of the frame. Two slide bars 140, 140' are mounted to rest in the slots 117, 117' and to extend through the guide holes 141 of the frame. The slide bars 140, 140' are mounted to rest in the slots 117, 117' and to extend through the guide holes 141 of the frame. The slide bars 140, 140' extend through the rear end 114 of the frame and have mounted on the outer ends thereof short vertical bars 142, 142' respectively, each of which contains a vertical slot 143 extending in from its lower end. Slots 143 embrace eccentrics 144, 144' mounted on opposite ends of a transverse shaft 145 which is positioned below the bottoms of recesses 120, 121 and is journaled in a bracket 146 secured to the rear end 114 of the frame. In an operative condition the shaft 145 is rotated at high speed, being driven, for example, by a belt passing over a pulley wheel 147. The rotation of the shaft causes the eccentrics 144, 144' to give the slide bars 140, 140' a rapid reciprocatory movement. This movement is very short owing to the fact that the throw of the eccentrics 144, 144' is only a few hundredths of an inch, being exaggerated in the drawings for the sake of clearness.

The cleaner is provided with reciprocatory elements which serve to clean the yarn and to direct the matter removed from the yarn out of the cleaner. Two types of such elements, the cleaning elements 150, 150' and the cleaning and deflecting elements 170, 170', are shown in the drawings.

Each reciprocatory cleaning element 150 comprises a cleaning blade 153, inclined towards the front end 113 of the frame, and a support 152, inclined toward the rear end of the frame, and pivotally secured at its outer end to the slide bar 140 by means of screw 156. Each support 152 contains a slot 157 which embraces a pin 158 on the side 115 of the frame. As a result, reciprocatory movement of the slide bar 140 moves the inner edges of the blades 153 in a curve tangential to the yarn. The pins 158 are positioned so that the inner edges of the blades 153 are close to the yarn at the middle point of each reciprocation of the slide

bar 140. The supports 152' of the elements 150' are mounted in the same way as the supports 152.

In the end of each of the cleaning blades 5 153, 153' is a semi-circular notch 159, 159' respectively extending substantially parallel to the slide bars. The cleaning elements 150, 150' are positioned in staggered relation with the centers of their notches 159, 159' 10 aligned. These, therefore, partly encircle opposite sides of the yarn A.

Each cleaner and deflecting element 170 comprises a support 172 and a blade 173 extending straight inward from the inner 15 end of the support and inclined rearwardly and downwardly. The blade has a straight edge 175 which is perpendicular to the support 172 and is inclined to the line of the travel of the yarn by reason of the inclination of the blade. The cleaning and deflecting elements 170' are similar to the elements 170 except that each of them has in its inner edge 175' a semi-elliptical notch 180 extending substantially parallel to the slide 25 bars.

The supports 172 of alternate elements 170 are pivotally secured at their outer ends to the side 115 of the frame 110 by means of screws 176 located inside the slide bar 140. 30 Each support 172 contains a slot 177 which embraces a pin 179 on the slide bar 140. The supports 172' of the other elements 170 are pivotally secured to the side 115 of the frame by means of screws 176' located outside the slide bar 140. Each support 172' 35 contains a slot 177' which embraces a pin 178' on the slide bar 140. The pins 178, 178' are positioned so that at one end of the reciprocatory movement of the slide bar 140 40 the supports 172 are inclined slightly towards the rear end 114 of the frame and the supports 172' are perpendicular to the side 115 of the frame, placing the blades 173 in the position illustrated in Fig. 1, while at 45 the other end of the reciprocatory movement of the bar 140 the supports 172 are perpendicular to the side of the frame and the supports 172' are inclined slightly toward the rear end of the frame. The supports 50 172' and 172' are mounted on the side 116 of the frame and the slide bar 140' in the same manner as supports 172, 172'.

As the pivotal axes of the elements 170, 170' are vertical, the upper end of the inner 55 edge 175 or 175' of each blade 173 or 173' moves in a curve tangential to the center line of the frame, while, owing to the inclination of the blades, the lower end of the inner edge of each blade is moved outwardly to a greater extent than the upper end of the inner edge. As a result when a pair 60 of elements 170, 170' are turned rearwardly the inner edges 175, 175' and the blades 173,

173' diverge from each other towards their lower ends.

65

In the operation of the cleaner the reciprocation of the slide bars 140, 140' causes the inner edges of the blades to reciprocate in directions substantially longitudinal of the yarn and causes the edges of the notches 70 159, 159', 180 in the blades 153, 153', 173' to brush and scrape from the yarn specks and impurities projecting from it. Owing, however, to the slight outward component in the reciprocatory movement of the blades 75 153, 153' and to the inclination of these blades, they serve to hook particles off the yarn in addition to their brushing action. The outward turning of the blades 173, 173' serves to release any fibrous matter which 80 may have become caught between the inner edges of a pair of these blades. As the pair of blades turn outwardly alternately so that the inner edges of all the pairs are not separated widely at any one time, no particles or 85 fibrous matter can be drawn through the cleaner without being deflected downwardly by one or another of these pairs of blades.

It is to be understood that the present invention is not to be limited by the illustrated 90 embodiment, but only by such equivalent structures as come within the scope of the appended claims.

What is claimed is:

1. In a yarn cleaner for removing particles from a traveling yarn, two pairs of transverse blades located so that the yarn passes successively between the inner edges of the blades of each pair, and means for causing alternate separating movements of 95 the blades of each pair.
2. In a yarn cleaner for removing particles from a traveling yarn, two pairs of transverse blades located so that the yarn passes successively between the inner edges of the blades of each pair, and means for alternately turning the blades of each pair 100 outwardly from each other.
3. In a yarn cleaner for removing particles from a traveling yarn, a member located at one side of the yarn, means for reciprocating said member in directions 110 parallel to the yarn, and a plurality of transverse blades mounted on said member 115 and having edges in contact with the yarn.
4. In a yarn cleaner for removing particles from a traveling yarn, a transverse blade having an edge adjacent to the yarn, a pivoted support for said blade permitting said edge to move in directions approximately longitudinal of the yarn, and means for reciprocating said support.

In testimony whereof I have hereunto set my hand.

HENRY E. VAN NESS.
